UNITED STATES PATENT OFFICE.

JOSEPH M. NORMAND, OF SPRINGFIELD, OHIO, ASSIGNOR OF ONE-HALF TO
JACOB KREIDER MOWER, OF SAME PLACE.

PUMP.

SPECIFICATION forming part of Letters Patent No. 325,623, dated September 1, 1885.

Application filed March 5, 1885. (No model.)

To all whom it may concern:

Be it known that I, JOSEPH M. NORMAND, a citizen of the United States, residing at Springfield, in the county of Clark and State 5 of Ohio, have invented certain new and useful Improvements in Pumps, of which the following is a specification.

My invention relates to that class of pumps in which two cylinders of different capacities are arranged one above the other in such a manner that only half of the water drawn up by the lower and larger cylinder is discharged on the upstroke, the other half being received by the upper and smaller cylinder and discharged by the downward stroke, whereby a constant stream is maintained at the discharge-pipe.

The object of my invention is to simplify and cheapen the construction of pumps of this 20 class, and to provide for discharging the water from the lower end of the upper cylinder without increasing the diameter of the pump beyond the extreme diameter of the lower pumping-cylinder; and, further, to provide for 25 discharging the water through the pump-stock without closing the upper end of the upper cylinder or incasing the pump-rod, at the same time dispensing with stuffing-boxes of any kind.

My invention consists in the arrangement 30 of two pumping-cylinders of unequal diameter eccentric to each other, and providing a water-passage from the lower end of the upper cylinder opening into the discharge-pipe.

My invention further consists in the arrangement of the eccentrically-located pumping-cylinders with a water-delivery stock 35 provided with a drop-pipe adapted to form an air-chamber in said stock.

My invention further consists in various 40 other constructions and combinations of parts, hereinafter described and claimed.

In the accompanying drawings, Figure 1 is a vertical sectional elevation of a pump embodying my invention. Fig. 2 is a top view 45 of the cylinders, showing the upper piston-rod in section. Fig. 3 is a perspective view of the top or head of the pump. Fig. 4 is a sectional view showing the arrangement of the pumping-cylinders for deep-well pumps. Fig. 5 is a plan view of the lower pump-valve.

Figs. 6 and 7 are a vertical sectional elevation and plan view, respectively, showing a modified form of the cylinders; and Fig. 8 is a detailed view of one of the pistons, shown partly 55 in section.

In the said drawings, A represents the upper and B the lower cylinder, and A' and B' the respective pistons therefor. The upper cylinder, A, I preferably make of a straight 60 round tube of brass or other suitable material, screw-threaded at the top and adapted to be screwed into an opening, a, in the upper end of a casing, C, so as to depend into said casing. This casing C is cylindrical in shape at 65 the bottom, and is adapted to be secured to the top of the lower cylinder, B. The casing C may be secured directly to the top of the lower cylinder, B, as shown in Fig. 1, or by providing caps D D' and pipe D', as shown in 70 Fig. 4. The lower cylinder may be located at any desired distance below the said casing. The casing C is supported by the pump-stock E, which is connected to a neck or projection, b, on the top of the casing C. This neck b is 75 offset over the opening a, into which the upper cylinder is secured, and is connected by a passage, c', to the inside of the casing C. The upper piston, A', is provided with a stem, d, 80 preferably cast thereon, said stem being provided with a longitudinal slot, d', and adapted at its upper end to be connected to the reciprocating pump-rod e. This piston-stem d is adapted to bear against the neck b, which is extended over to the center of the upper cylinder, A, the stem being preferably cast on an arc corresponding to the curve of the neck b. A bolt, f, provided with an enlarged head and adapted to pass through the longitudinal slot d', is screwed into the side of the neck b, 85 and serves to hold the piston-stem d against lateral movement thereon, at the same time permitting longitudinal movement of said stem.

The top of the pump-stock E is surmounted 95 by a cap or head, E', provided on one side with a laterally-projecting lug, g, adapted to form a bearing for the oscillating handle F, to which it is attached by a bolt or pin, g'. The handle F is bifurcated at the upper end 10 and projects forward on each side of the head E', and is connected by means of a bolt or

pin, *h*, to a T-shaped connecting-piece, *h'*, which is secured on the end of the reciprocating pump-rod *e*. The pump-head *E'* is reduced at its upper end and tapped out to receive the end of a drop-pipe, *H*, which is screwed therein and extends downward into the pump-stock, thereby forming a discharge-opening for the water, and at the same time creating an air-chamber in the upper part of the pump-stock *E*. The pipe *H* extends only part way through the reduced portion of the pump-head *E'*, said head being long enough to receive the end of a curved pipe, *H'*, which is screwed therein and forms the pump-spout or discharge-pipe proper. This spout *H*, extending as it does from the center of the top of the head, is adapted to be turned to any relative position with the handle *F*—a point of considerable advantage in locating pumps in crowded places. By providing a lock-nut, *i*, on said pipe means are furnished for securing the spout in any desired position and at the same time making a tight joint.

The lower end of the lower cylinder, *B*, is closed by a cap, *I*, adapted to receive at its lower end the inlet-pipe *J*, which is secured therein. Immediately above the inlet-pipe *J* a recess, *k*, is formed in the cap, adapted to receive a ring, *l*, of hard or vulcanized rubber, adapted to form a seat for the valve *m*. This valve *m* is made from a leather gasket, which extends over the top of the cap and between the said cap and the end of the cylinder, the said gasket being cut out, as shown in Fig. 5, to form the valve, and a weight, *m'*, placed on top thereof, as shown. The leather valve, as thus described, in combination with the rubber valve-seat, makes a very tight-closing valve, not liable to rust or stick. This construction, however, will be made the subject of another application, and is not therefore claimed in this.

The connection between the upper and lower piston I preferably make by means of a straight piston-rod, *n*, which is screw-threaded at its upper end and tapped into the bottom of the upper piston eccentric thereto.

The pump-pistons are provided, in the usual way, with a packing-ring, *p*, of leather, which is compressed into the shape of a ring with an internal annular flange. In order that the packing may be readily applied or removed, as desired, I provide on the lower side of the piston a boss or neck, *p'*, equal in diameter to the internal diameter of the said annular flange. This boss *p'* is screw-threaded and provided with a nut, *p''*, adapted to screw thereon and bind against the annular flange of the packing-ring *p*, the external diameter of the nut being equal to the internal diameter of the packing-ring.

In the bottom of the neck *b*, where it extends over the upper cylinder, *A*, I provide an inwardly-opening valve, *o*, provided with an outwardly-projecting stem, adapted, when the piston *A'* is raised to its limit by the downward stroke of the handle *F*, to be en-

gaged by said piston, and thus open the valve, thereby automatically draining the pump-stock and preventing the freezing of the same.

If desired, a variable stop may be provided for the handle *F*, so that when desirable the handle can be stopped on its downward stroke at a point not sufficiently advanced to open the valve *o*.

The action of the pump is obvious. The lower piston, *B'*, is provided with an ordinary drop-valve, which permits the water to rise through said piston on the downstroke, and as the piston is drawn up the water in the lower cylinder is partly discharged through the stock *E* and discharge-pipe *H*, and partly drawn into the upper cylinder, *A*, and is discharged on the downstroke of said piston. As the water is forced up into the pump-stock it meets the column of air which surrounds the drop-pipe *H* in the top of said pump-stock, and is thus discharged in a steady and constant stream at the spout *H*.

By the construction above described a simple and very compact construction is secured, the whole being confined in diameter to the outer limits of the casing *C*. The top of the upper cylinder is left open, thus dispensing with the use of stuffing-boxes. A very large pump-stock is secured, permitting the air-chamber to be formed immediately therein.

In Figs. 6 and 7 I have shown a modification in which both cylinders are cast in a single piece and eccentric to each other.

Other modifications will suggest themselves to an ordinary mechanic.

Having thus described my invention, I claim as new and desire to secure by Letters Patent—

1. The combination, with the pump-stock, of two pumping-cylinders eccentric to each other, and a water-passage from the bottom of the upper cylinder to the pump-stock, whereby the water is discharged through said pump-stock without closing the top of the upper cylinder or incasing the pump-rod, substantially as set forth.

2. The combination, with the eccentric pumping-cylinders, of the outer casing, forming a passage from the bottom of the upper cylinder, and provided with a neck offset oversaid upper cylinder, into which the pump-stock is secured, substantially as set forth.

3. The combination, with the pumping-cylinders, of an outer casing adapted to be connected at its lower end to the lower cylinder, and provided at the top with two openings on opposite sides thereof, one of said openings being adapted to receive the end of the upper cylinder, which depends into said casing, and the other adapted to receive the end of the pump-stock connected thereto, whereby the cylinders are placed eccentric to each other, and a water-passage formed from the bottom of the upper cylinder to the pump-stock, substantially as specified.

4. The combination, with the eccentric cyl-

inders, of an outer casing provided with a neck offset over said upper cylinder, a piston-stem provided with a longitudinal slot therein, connected to the upper piston, said piston-stem being adapted to bear against said neck and held against lateral movement thereon by a bolt extending through said longitudinal groove, substantially as specified.

In testimony whereof I have hereunto set my hand this 26th day of February, A. D. 1885.

JOSEPH M. NORMAND.
